SHEDDING MECHANISM FOR LOOMS

Frank W. Preston, Paterson, N. J.

Application March 12, 1936, Serial No. 68,365

7 Claims. (Cl. 139—59)

This invention relates to shedding mechanism for looms and particularly to jacquard machines and it has for its object to provide in such machines for the possibility of lifting threads of the warp not only to a plane which will cause one shed to be formed but to a higher plane so that a more elevated shed may also be formed. Where as the improvements may be incorporated in a jacquard machine initially, they are herein so devised that they may be incorporated in existing jacquard machines without extensive or expensive alteration thereof. The improvements, as will appear to those skilled in the art, make possible various advantages in weaving, among which is that of weaving two fabrics by approximately the same weaving operation as and in substantially the same time now required for the weaving of a single fabric, notably of the narrow-ware class. By the terms "lifter", "lift", "lifting", or "lifted" herein anywhere used I do not wish to be limited to upward motion since I mean thereby to include such motion as involves displacing the warp threads (in order to form the sheds) in a given direction from the plane they normally tend to assume.

In the drawing,

Fig. 1 is a side elevation, somewhat diagrammatic, of a jacquard machine and shows the present improvements;

Fig. 2 is a section on line 2—2, Fig. 1, of the auxiliary hook-lifting structure, with fragments of a row of hooks and the corresponding knife in elevation;

Fig. 3 is a section on line 3—3, Fig. 1, of the means whereby motion is transmitted to such structure;

Fig. 4 is a section on line 4—4, Fig. 2, and shows fragments of a knife and hook and a hook-lifter;

Fig. 5 is a diagram illustrating a weaving operation possible by the invention, the view being transversely of the warp; and

Fig. 6 is a view similar to Fig. 4, showing a modified construction.

Let 1 be the frame of any jacquard machine mounted as usual on supports 2; 3 the usual knife frame having the knives 4; 5 vertical shafts to which the knife frame 3 is affixed and being guided to move vertically in the frame 1 and forming with such knife frame what I term the main hook-lifting structure; 6 one of two levers (or it may be one of the arms of a forked lever) which are rocked in unison from any going part of the loom and which are adapted to reciprocate vertically said main hook-lifting structure, being connected to the shafts through links 7; 8 the

hooks in rows and resting on the bottom board or other support 9 of frame 1 and capable of tilting thereon to the left, otherwise having their catching portions or hooks proper 8a overhanging the knives so that the hooks may be lifted by the knives; 10 the needles suitably guided in the frame 1 to move horizontally and respectively connected with the hooks (as by having loops 10a receiving them) so that when any needle is moved to the left (it being understood that the needles are normally held against such movement, as by springs, not shown, it will tilt the corresponding hook to the position to clear the knife adapted to lift the same; 11 the card cylinder adapted to be turned a quarter-turn and then moved toward the needles previous to each rise of said main hook-lifting structure by means not shown but well known in the art; and 12 the cards carried by the cylinder and punched according to a given pattern so that, when the card cylinder is moved toward the needles, the card then presented thereto will shift some of the needles and corresponding hooks to the left to clear the knives according to the punching of such card. To each hook is connected a cord 13 which in turn is connected to and so is adapted to lift some thread of the warp, such cords being shown dotted for a purpose to appear.

According to the invention I provide an auxiliary hook-lifting structure which preempts the main hook-lifting structure in its hook-lifting function with respect to but some of the whole complement of hooks and which is moved to lift such hooks to a greater extent than the main hook-lifting structure; preferably it comprises a grid or other frame in which there are hook-lifters capable of being positioned therein each to lift some particular hook or hooks. This auxiliary hook-lifting structure undergoes hook-lifting motion on each such motion of the main hook-lifting structure, and this I accomplish, according to the present example, through means actuated from such main hook-lifting structure, though it may be otherwise accomplished.

In the example a fixed frame 14 is mounted on the frame 1 and forms therewith what I term the fixed supporting structure and the shafts 5 are prolonged upwardly and guided in frame 14. The auxiliary hook-lifting structure includes a grid 15 penetrated by and adapted to slide vertically on said shafts. Such auxiliary hook-lifting structure also includes hook-lifters 16. Each of the latter may occupy, as stated, any of various positions on the grid so that it may be effective to lift some particular hook. As shown, each bar

15a of the grid is longitudinally slotted and each hook-lifter stands in a vertical plane lying between a row of hooks and the corresponding knife and is formed with a bent-off portion 16a lying 5 in the path of movement of the top edge of the knife and affording a shoulder to engage the catching portion 8a of the corresponding hook; each hook-lifter is here formed by a suitably bent blade. In the present case the blade depends 10 from a bar of the grid and it has a terminal 16b which is secured to such bar by a bolt 17 penetrating the slot of the bar, the length of said terminal being such that when the auxiliary hook-lifting structure is fully depressed the corresponding 15 hook (or hooks) may be tilted on support 9 so as not to be raised by said structure when it rises. According to the example, any hook-lifter may be shifted along the corresponding bar of the grid so as to be active to lift a hook (or hooks) 20 at any point in a row of hooks otherwise adapted to be lifted by a given knife; and there may be more or less hook-lifters on any bar and it is not to be assumed from the showing of Fig. 2 that there will necessarily be hook-lifters only on some 25 of the bars.

The extent of rise of the auxiliary hook-lifting structure is to be greater than that of the main hook-lifting structure so that the hooks lifted by the former will raise the warp threads controlled thereby higher than those raised by hooks lifted by the main hook-lifting structure. This may be accomplished in any way but I prefer to impart the differential movement to the auxiliary from the main hook-lifting structure as shown by 30 Figs. 1 and 3. Here a lever 18 is fulcrumed on the fixed supporting structure at 18a and here pivotally connected to the auxiliary hook-lifting structure by a link 19. In the example a link 20 and a bracket 21 fixed on the shaft 5 afford the 35 connection between the main hook-lifting structure and the lever 18. The pivots for connecting link 20 with the lever and bracket are studs 22 each having a shoulder 22a between which and a nut 23 the lever 18 (or bracket 21) is clamped, the lever being retained on the stud by a nut 24; the lever and bracket are slotted, at 18b and 21b, to receive the studs which thus may be adjusted 40 to vary the lift of the auxiliary hook-lifting structure imparted thereto by the main hook-lifting structure due to the thus described motion-transmitting connection connecting them. Of course, when the adjustment is such that the pivots occupy the ends of the slots adjoining shaft 5 the lift effected by the auxiliary will be of the 45 same extent as that of the main hook-lifting structure, so that the machine may be operated as if my improvements were not present.

Parts 18, 19, 20 and 21 will usually be duplicated at the far side of the machine.

60 Suppose a certain number of the hooks of the jacquard are left subject to the lifting action of the main, and the remainder made subject to the lifting action of the auxiliary, hook-lifting structure, the latter being assumed, as explained, 65 to effect a greater extent of lift substantially coincident with the lifting action of the former, as by being actuated through the motion-transmitting means described. All the hooks which, by the described pattern mechanism, are displaced to the left will remain unlifted; of those not so displaced some will be lifted as far as the knives are lifted and some higher than the knives are lifted according as they are left subject to the lift of the knives or that of the hook-lifters, 70 wherefore the threads of the warp controlled by

these three sets of hooks will form two sheds, one at a higher elevation than the other.

Various possibilities in weaving therefore exist.

Suppose it is desired to weave two fabrics, as 5 ribbons, in one operation, as shown by Fig. 5, where the warp threads *a* are to form two sheds *b* and *c* through which two shuttles *d* are to be respectively passed, one shed beside and higher 10 than the other. The threads in the plane *x* are those whose hooks remain unlifted and form the bottom sheet of shed *b*; the threads in plane *y* are those whose hooks have been lifted by the main hook-lifting structure and form the top sheet of shed *b* and the bottom sheet of shed *c*; and those in plane *z* are those whose hooks have 15 been lifted by the auxiliary hook-lifting structure. Now since each thread shown in the upper sheet of shed *c* can only assume a position in either plane *x* or *z* because it is connected, by a connection such as 13, with a hook individual to such thread and itself capable of only assuming positions spaced correspondingly to planes *x* and *z* it would be impossible to form sheds next succeeding to the existing sheds *b* and *c* (in order 20 to decussate or cross and so to weave) without having the new shed to be formed and corresponding to shed *c* aligned with the new shed corresponding to shed *b*, since the only position the threads shown in the top sheet of shed *c* can 25 next assume in plane *x*, or the position where their hooks are left unlifted. What is necessary in such case is to provide for the threads which go to form the shed *c* being each shiftable not only to plane *z* but to plane *y*, which may be accomplished as follows (it remaining assumed that the threads going to form sheds such as *b* remain subject to the action of the main hook-lifting structure and of course to the control, for decussating, of the pattern mechanism):

40 Each thread which goes to form shed *c* may have a flexible connection 13a which is branched as at 13b, one branch depending from a hook which is liftable by the main, and the other depending from a hook which is liftable by the auxiliary, hook-lifting structure. Then, according as either of its hooks is left by the pattern mechanism in position to be lifted by the corresponding hook-lifting structure, so such thread will assume the corresponding plane *y* or *z*. In short, each thread is then subject to the lifting action of either hook-lifting structure, wherefore on one lifting action of the machine some threads may be lifted to plane *y* and the remainder to plane *z*, and on the next lifting action the former threads may be lifted to plane *z* and the latter to plane *y*. Thus, decussating, and hence weaving in the same kind or pattern of weave at the right as at the left of Fig. 5, may be accomplished.

55 Of course in such a case the warp of the fabric could not include as many "ends" or threads as there are hooks (since as to a part of the whole complement of hooks each end is served by two hooks) wherefore I have devised the construction shown by Fig. 6. Here the hook-lifter 16 for any 60 thread has a yoke 22 loosely penetrated by a stiff extension 23 of the corresponding hook to which it is preferably pivotally connected, as shown. Above the yoke the extension has an adjustable stop as nuts 24, screwed thereon. When the hook 65 is left by the pattern mechanism in position for its catching portion 8a to be engaged by the shoulder 16a of the hook-lifter there will be lifting of the thread to its highest position; when the hook is displaced by the pattern mechanism 70 75

so as to clear the shoulder there will first be lost-motion during the rise of the hook-lifter until its yoke engages the stop 24, whereupon it will lift the hook to a mean position and hence the 5 thread to plane y. A single hook controls a corresponding thread or end and the connection is like 13, or unbranched. In this case the warp may contain as many ends or threads as there are hooks in the jacquard. By adjusting stops 10 24 and the links 20 the extent of lift to the highest or to the mean position may be varied as circumstances require.

Having thus fully described my invention what I claim is:

15 1. A jacquard machine including supporting means, hooks supported thereby and adapted to be lifted, hook-lifting structures, and a lever fulcrumed on said supporting means and to which said structures are operatively connected at different distances from the lever fulcrum and affording support for one structure on the other, some of said hooks being each movable into and out of position to be lifted by one and others each movable into and out of position to be lifted 20 by the other of said structures.

25 2. A jacquard machine including supporting means, hooks supported thereby and adapted to be lifted, hook-lifting structures, a lever fulcrumed on said supporting means and to which one structure is operatively connected, pivots on the other structure and said lever, the pivot on the lever being adjustable lengthwise thereof, and a link connecting the pivots, said lever, pivots and link affording support for one structure on 30 the other, and some of said hooks being each movable into and out of position to be lifted by one and others by the other of said structures.

35 3. A jacquard machine including supporting means, a hook-lifting structure movable in a given path therein, hooks supported in said means and having catching portions and each movable into and out of the position where its catching portion will lie in the path of said movement of said structure, and another hook-lifting structure 40 having a shoulder in the path of the first-named structure and between the same and the catching portion of a given hook when the latter is in said position, the second-named structure being movable in generally said direction through 45 a greater range than the first-named structure.

4. A jacquard machine including supporting means, a hook-lifting structure movable in a given path therein, hooks supported in said means and having catching portions and each movable into and out of the position where its catching portion will lie in the path of said movement of said structure, a supporting structure, and a hook-lifter having a shoulder and positionable in the latter structure to place said shoulder in the path of the first-named structure and between the same and the catching portion of a selected hook when the latter is in said position, the second-named structure being movable in generally said direction through a greater range than the first-named structure. 5

10 5. A jacquard machine including supporting means, hooks supported thereby and adapted to be lifted, hook-lifting structures movable one through a greater range than the other, some of said hooks being each movable into and out of position to be lifted by one and others being each movable into and out of position to be lifted by the other of said structures, and flexible thread-lifting cords, each cord being branched and having one branch connected to one of the first-named and the other branch connected to one of the second-named hooks. 15

20 6. A jacquard machine including supporting means, a lifting structure movable through a given range and having a lifting shoulder, and a thread-lifting device having a catching portion to be engaged by said shoulder and said device being movable into and out of position where said catching portion will be so engaged by said shoulder, said device having a stop arranged to 30 be engaged by said structure during the movement of the latter through said range when said device is out of said position. 35

25 7. A jacquard machine including supporting means, hooks supported thereby and adapted to be lifted, rectilineally movable hook-lifting structures, and means, affording support for one structure on the other structure, to transmit differential lifting movement from the latter structure to the former structure when said latter structure is lifted, some of said hooks being each movable into and out of position to be lifted by one and others each movable into and out of position to be lifted by the other of said structures. 40
